THE NORRIS METERS CO. PHOTO-LITHO, WASHINGTON, D. C.

UNITED STATES PATENT OFFICE.

WILLIAM N. PELOUZE, OF CHICAGO, ILLINOIS.

DESIGN FOR A CASING FOR WEIGHING-SCALES.

SPECIFICATION forming part of Design No. 27,466, dated August 3, 1897.

Application filed June 30, 1897. Serial No. 643,031. Term of patent 14 years.

To all whom it may concern:

Be it known that I, WILLIAM N. PELOUZE, a citizen of the United States, residing at Chicago, in the county of Cook and State of Illinois, have invented and produced a new and original Design or useful Shape for a Casing for Weighing-Scales, of which the following, in connection with the accompanying drawings, is a full, clear, and exact specification.

10 In the said drawings, Figure 1 is a perspective view of a scale-casing embodying my design, and Fig. 2 is a rear elevation thereof.

The leading features of my design consist of the base A and the body portion B, having 15 a semicircular dial C.

The base A is substantially flat with beveled edges *a* and is of slightly-greater dimensions than the adjoining edge of the body portion B and dial C.

20 The body portion B is semicylindrical when viewed from the rear, as in Fig. 2, and is of

less thickness than the diameter of the arc by which its sides are bounded.

The scale-plate 2 rises perpendicularly from the base A at one end of the body portion B 25 and is arranged in a frame-like portion D, which is of slightly-greater diameter than the body portion B, and whose edge is parallel therewith, as clearly shown in Fig. 2.

Upon the top of the body portion is arranged 30 a knob E.

Having thus described my invention, what I claim as new therein, and desire to secure by Letters Patent, is—

The new and original design or useful shape 35 for casing for weighing-scales, substantially as herein shown and described.

WM. N. PELOUZE.
